UNITED STATES PATENT OFFICE.

CHARLES R. WOOD, OF FARGO, NORTH DAKOTA.

RULE POCKET.

1,407,827.

Specification of Letters Patent. Patented Feb. 28, 1922.

Application filed September 25, 1920. Serial No. 412,764.

To all whom it may concern:

Be it known that I, CHARLES R. Wood, a citizen of the United States, residing at Fargo, in the county of Cass and State of North Dakota, have invented certain new and useful Improvements in Rule Pockets, of which the following is a specification, reference being had to the accompanying drawings.

- 10 In the old style of rule pockets for mechanics' overalls, the rule or other article may easily fall out, and when the rule or other article is small, it is difficult to extract the same. Furthermore, the flap of the old style pocket frequently outwardly projects, therefore, it will catch on protuberances which may be in its path.
- 20 In the present invention the above disadvantages are overcome, in providing a pocket from which the rule or other article may be easily extracted and wherein the flap or the like is eliminated, avoiding catching on any projecting object. Also the rule cannot easily fall out as the opening to the pocket is constructed to hold the rule therein securely.
- 25 The invention has for its purpose to provide a rule pocket having on its exterior, a double pencil pocket for the accommodation of different lengths of pencils.

- 30 A further object is to provide a rule pocket, wherein the flap (which is constructed as not to project outwardly as in the present instance) is dispensed with, as well as the double pencil pocket, hence cheapening and simplifying the construction of the pocket.

- 35 While the design and construction at present illustrated and set forth is deemed preferable, it is obvious that as a result of a reduction of the invention to a more practical form for commercial purposes, the invention may be susceptible of changes, and the right to these changes is claimed, provided they are comprehended within the scope of what is claimed.

- 40 The invention comprises further features and combination of parts, as will be herein-after set forth, shown in the drawings and claimed.

- 45 In the drawings:

- 50 Figure 1 is a view of a fragmentary portion of a mechanic's garment, showing the application of the improved rule pocket and the same constructed in accordance with the invention.

Figure 2 is a vertical sectional view on line 2—2 of Figure 1.

Figure 3 is a vertical sectional view on line 3—3 of Figure 1.

Figure 4 is a horizontal sectional view on line 4—4 of Figure 1.

Figure 5 is a horizontal sectional view on line 5—5 of Figure 1.

Figure 6 is a view in elevation of the inner face of a portion of the garment, showing the pocket applied, and illustrating a portion of the material of the garment cut away, thereby illustrating the interior of the pocket and the manner of folding the edges of the opening to the pocket.

Figure 7 is a view in elevation of a portion of a mechanic's garment, showing a modified form of rule pocket constructed in accordance with the invention and applied thereto,

Figure 8 is a sectional view on line 8—8 of Figure 7, and

Figure 9 is a transverse sectional view on line 9—9 of Figure 7.

Referring to the drawings, 1 designates a portion of a garment which may be constructed of any suitable material and 2 denotes a piece of similar fabric which is stitched at 3 to the garment 1. This piece of fabric 2 may be any length and width, sufficient to accommodate the length of a foldable rule. This piece of fabric 2 forms the exterior wall of the pocket and is made wider at the top than at the bottom, in order to hold the rule more securely within the pocket when the mechanic is in a bending or stooping posture. The exterior wall or fabric piece 2 of the pocket has an opening 4, to permit access to the interior of the pocket. In order to form this opening, the exterior piece is slitted at a point substantially midway its upper and lower ends, and one edge of the slit is whipped with a buttonhole stitch, as indicated at 5. The exterior wall or fabric piece 2 is then slitted vertically upwardly from the transverse slit, after which the edge portions of the vertical slit are folded back and are stitched as shown at 6, as shown clearly in Figure 6 of the drawing. It will be noted that the opening 4 is substantially V-shaped, so as to permit of a ready insertion and removal of the rule or other article. The exterior wall or fabric piece 2 of the pocket, before it is stitched to the garment has its marginal edge portion

105

110

undeturned, so as to present a neat appearance from the exterior. Arranged transversely of the pocket immediately adjacent the lower end of the opening 4 is a transversely disposed piece of fabric 7. This transverse piece of fabric is cut away to conform to the opening 4, as indicated at 8, and the lower edge of the cut away portion is also whipped-stitched by the stitches 5. 10 The vertical edge portions of the cut away portion 8 are engaged under the folded edge portions of the vertical slit, portions of the stitches 6 acting to hold the transverse piece of fabric 7 in position. Also, as shown 15 clearly in Figure 5, the side edges of the transverse piece of fabric 7 are engaged between the undeturned portions 9 of the exterior wall of the pocket, and the body of said wall, and are also fastened by the 20 stitches 8. The transverse piece of fabric 7 causes to be formed a pair of pencil receiving pockets 10. In other words, pencils or the like may be inserted between the transverse piece of fabric 7 and the exterior wall 25 of the pocket, while the rule or other article may be inserted through the opening 4.

As shown in Figures 1 to 6 inclusive, a cover or flap 11 is provided for the opening 4 to the pocket. To provide this cover, the 30 fabric constituting the cover is first stitched at 12 to the exterior wall or fabric piece 2, at a point immediately below the lower or wider end of the opening 4. The cover 11 is then folded upon itself, as shown in Figure 2, so as to obscure the stitches 12. The cover 11 extends from the upper forward edge of the exterior wall 2 of the fabric, in a direction towards the rear edge of the exterior wall 2. In other words, the cover 11 35 extends rearwardly a little beyond the rear edge of the opening 4 to the pocket. This cover is also stitched by the same stitches 3, which secure the wall 2 to the material of the garment, that is to say, after the cover 40 has been folded upon itself adjacent the stitches 12. This cover has a portion 13 folded upon itself as indicated at 14, and the folded part and the body of the cover are stitched as indicated at 15 to the forward 45 marginal edge of the opening 4. A portion of the cover 11 between the forward upper portions of the stitches 3 and the stitches 15 is provided with a pair of transverse slits 16, constituting openings to the compartment between the forward portion of the cover 11 50 and the piece of fabric 2, which is stitched to the garment. This compartment is designed to receive pencils of different lengths. In fact, a pencil of one length may be inserted through the lower opening 16, while a pencil of another length may be inserted through the upper opening 16. These openings 16 have their edges provided with button-hole stitches, to prevent ravelling of the 55 edges of the opening, as well as rendering

the openings more durable and more serviceable. In using the cover as shown in Figures 1 to 4 inclusive, the forward marginal edge of the opening 4 is folded between the fabric piece 2 of the pocket and the cover, thereby providing a neater and more practical construction. 70

When stitching the cover 11 to the fabric piece 2, the stitched edge portions of the cover are first folded under the fabric piece 2, after which the stitches are applied. This construction is shown clearly in Figure 4. 75

In Figures 7, 8 and 9 the cover for the pocket is eliminated, otherwise, the construction of the pocket is the same as that previously described, and illustrated in the drawings, therefore the parts of the construction shown in Figures 7, 8 and 9 are designated by the same characters as heretofore used. 80

The invention having now been set forth, 85 what is claimed as new and useful is:—

1. In a pocket for mechanics' garments, a portion of a garment, a fabric piece fastened to the garment, the fabric of the garment and the piece forming the interior and exterior walls of a pocket to receive a rule, 90 said exterior wall having an elongated opening to permit access to the interior of the pocket, and a transverse piece of fabric fastened between the vertical edge portions 95 of the outer wall of the pocket and the garment, said transverse piece being separable at points between the forward and rear edges of the opening and the fastening means between the exterior wall and the garment 100 wall, thereby providing interior pencil holding means.

2. In a rule pocket, a portion of a garment, a piece of fabric fastened to the garment and having its upper portion provided 105 with an elongated opening, said piece of fabric and the garment constituting the exterior and interior walls of the rule pocket, said opening to the pocket being V-shaped and having its forward and rear elongated edges 110 folded, and its lower transverse edge provided with a button-hole stitch, and a cover secured to the upper exterior face of the fabric piece overlying said opening, said cover having a double pencil pocket, for the reception of pencils of different lengths. 115

3. In a pocket of the kind set forth, a portion of a garment, a piece of elongated fabric fastened to the exterior thereof, the piece of fabric and portion of the garment 120 respectively constituting the inner and outer walls of a pocket, the outer wall of the pocket near its upper portion having an opening, a cover fastened to the fabric piece and overlying said opening, said cover having spaced 125 openings, thereby permitting of the reception of pencils of different lengths between the cover and a portion of said fabric piece.

4. In a pocket, the combination with a portion of a garment, a piece of fabric fas 130

tened to the garment and provided with an elongated opening at its upper portion, a cover attached to the piece of fabric over the opening with one edge free, thereby permitting access to be had to the interior of the pocket, a portion of said cover being attached along one edge of said opening, thereby causing a compartment to be formed between the cover and the piece of fabric, said

cover having an opening, to permit a pencil 10 to be inserted into said compartment, and a strip fastened to the inner face of the piece of fabric adjacent the lower part of said opening.

In testimony whereof I hereunto affix my 15 signature.

CHARLES R. WOOD.
